DIAL

Frederick Liessmann, Chicago, Ill., assignor to
 Electrical Research Laboratories, Inc., Chicago, Ill., a corporation of Illinois

Application October 7, 1935, Serial No. 43,890

9 Claims. (Cl. 116—124.1)

This invention relates to wave band indicators for radio receiving sets.

The invention has particularly to do with an indicator upon a tuning dial of a radio receiving set, such indicator being operated from the wave band selector means to indicate on the tuning dial which one of a number of scales thereon is to be referred to in tuning the set.

The objects of the invention include among others the provision of the following:

An improved wave band indicator;

Improved means of operating a wave band indicator in conjunction with a wave band selector switch;

An improved combination of multi-wave band dial and wave band indicator.

These objects and other objects which will hereinafter appear are obtained by the novel arrangement, combination and construction of elements hereinafter described and claimed. One embodiment of a device disclosing the invention is illustrated in the accompanying single sheet of drawing, hereby made a part of this application, and in which:

Figure 1 is a front view of a device embodying the invention;

Figure 2 is a sectional view of the device of Figure 1 on broken line 2—2 of Figure 1;

Figure 3 is an enlarged section of the central part of the same device on line 3—3 of Figure 2; and

Figure 4 is an enlarged section of the central part of the same device on line 4—4 of Figure 1.

Like reference characters are used to designate similar parts in the drawing and in the following description.

In radio sets adapted to receive on two or more separate wave bands, as for instance on the standard broadcast band, the amateur and police band, and foreign station band and the like, the change from one band to another is made by means of a band selector switch.

The same tuning condensers are used for each band. Some means must be provided for pointing out on the tuning dial a scale to which reference must be made in connection with the particular wave band selected.

The present device is intended for use on the conventional multi-band receiving set. The chassis of the set is indicated at 10. Usually mounted above the chassis are tuning condensers the front plate 11 of which is shown in Figure 2.

A condenser shaft 12 extends through the front plate. Mounted on the chassis proper is a wave

band selector switch having a shaft 13, a knob 14, one or more switch arms as indicated at 15, and one or more sets of switch points 16.

Attached to the condenser shaft 12 is a collar 17, secured to the shaft by a set screw 18, or by any other suitable means. The collar 17 carries a friction disk 19. The friction disk 19 is engaged by a friction wheel 20 mounted on tuning shaft 21 and operated from the front of the set by a knob 22 to rotate the condenser plates to tune the set. Mounted in line with the condenser shaft is a dial scale 23. Brackets 24 and 25 hold the dial 23 in position with respect to the chassis.

Printed or engraved on the front of the dial 15 scale 23 are four tuning scales, 26, 27, 28 and 29. Each scale is adapted for use in connection with one particular wave band which is to be selected by the wave band selector switch. More or fewer scales may be used on the dial according to whether the radio set is intended to cover more or less than four bands. Scales 26 and 27 are above the center of the dial and are to be used in connection with the upper end of a pointer. The lower scales 28 and 29 are to be used in connection with the lower end of the pointer.

Set into or forming a part of collar 17 is a hollow extension shaft 30. A collar 31 is threaded onto extension shaft 30 to secure friction disk 19 in place. The outer end of shaft 30 extends through a hole, indicated at 32, in dial scale 23. Mounted non-rotatively on the front end of shaft 30 is a pointer guide 33. A collar 34 on guide 33 extends about shaft 30 through the hole 32 in dial scale 23. A track 35 for a sliding pointer 36 is formed on a diameter of the pointer guide 33. The track 35 has a raised portion 37 to allow room for a cord 38. Cord 38 provides means for moving the pointer 36 endwise in either direction in the track 35. The cord 38 runs lengthwise along the front of the pointer 36. Near each end of the pointer it passes through an aperture indicated at 39 and passes along the back of the pointer from each end to the shaft 30.

The hollow at the front end of the shaft 30 is flared and curved outwardly at 40 to permit the cord 38 to move readily into and out of the hollow of the shaft without cutting or fraying. The hollow of shaft 30 continues into collar 17 to a slot 41 cut in collar 17. An arm 42 attached to the chassis 10 extends into slot 41 and carries an eyelet 43 within the slot 41 and opposite the mouth of the hollow through shaft 30.

The two ends of cord 38 extend through the hollow of shaft 30, through eyelet 43, and to a

pulley 44 mounted non-rotatively on shaft 13 of the wave band switch. Each end of the cord 38 passes partly about the pulley 44 and into an opening 45 in the pulley. Each end of the cord 5 is secured inside the pulley to one end of a spring 46. Spring 46 passes about the hub 47 of the pulley. The spring 46 keeps cord 38 uniformly under tension, and prevents its slipping on pulley 44.

10 In the form of device shown, the pointer 36 is two ended. The top end is adapted to pass across scales 26 and 27 on the dial. The lower end is adapted to pass across scales 28 and 29 on the dial.

15 The operation of the device is as follows: The wave band selector switch is adjusted or moved to select the desired wave band. Pulley 44 moves with the movement of the switch and pulls cord 38 a predetermined distance. Cord 38 pulls the pointer 36 up or down a selected amount according to which wave band is chosen. If the wave band is chosen with which scale 26 is used, the pointer 36 is extended fully upward to indicate scale 26. If the wave band covered by scale 20 28 is selected the pointer is moved fully downward to cooperate with scale 28. Likewise scales 25 27 and 29 are indicated upon the proper setting of the wave band selector switch. The selector switch and the pointer 36 having thus been set, 30 the set is tuned by rotating the condensers in the customary manner.

The pointer 36 and pointer guide 33 rotate with shaft 30, collars 34 and condenser shaft 12, the pointer moving across the selected scale on 35 the face of dial 23. The arm 42 and eyelet 43 are stationary, so that the two ends of the cord 38 maintain their respective positions in eyelet 43 and are twisted within the hollow of shaft 30 when the shaft and pointer are rotated.

40 What is claimed as new and is desired to be secured by Letters Patent of the United States is:

1. A wave band indicator for a multi-wave band radio set having a wave band selector 45 switch, comprising a dial having a scale thereon for each such wave band, a pointer rotatable over the face of said dial, and means to move said pointer longitudinally in a straight-line path through its axis of rotation to indicate a wave 50 band scale on said dial, said means comprising a continuously operable connection between said pointer and said selector switch.

2. A wave band indicator for a multi-wave band radio set having a wave band selector 55 switch, comprising a dial having a scale thereon for each such wave band, a pointer rotatable over the face of said dial, and means to move said pointer longitudinally to indicate one wave band scale on said dial, said means comprising a pulley operated by such selector switch, and a cord about said pulley and connected to said pointer.

3. A wave band indicator for a multi-wave band radio set having a wave band selector 60 switch, comprising a dial having a scale thereon for each such wave band, a pointer rotatable over the face of said dial, and means to move said pointer longitudinally to indicate one wave band scale on said dial, said means comprising a pulley operated by such selector switch, and a cord about said pulley and about a portion of said pointer.

4. A wave band indicator for a multi-wave band radio set having a wave band selector 75 switch, comprising a dial having a scale thereon

for each such wave band and an aperture through the center thereof, a hollow rotatable shaft extending from said radio set to such aperture in said dial, a pointer affixed to said shaft and rotatable over the face of said dial, and means to move said pointer longitudinally across said shaft, said means comprising a pulley operated by such selector switch, and a cord extending longitudinally of said pointer and about a portion thereof, through said hollow shaft, and about said pulley.

5. A wave band indicator for a multi-wave band radio set having a wave band selector switch and a tuning condenser shaft, comprising a dial having a scale thereon for each such wave 15 band and having an aperture through the center thereof, a hollow shaft rotatable with said tuning condenser shaft and extending to the aperture in said dial, a pointer guide affixed to said hollow shaft for rotation therewith and having 20 a pointer track thereacross, a pointer longitudinally movable in said pointer track, a pulley operated by said selector switch, and a cord extending longitudinally of said pointer and about a portion thereof within said pointer track through 25 said hollow shaft and about said pulley, said pointer being movable longitudinally by said cord when said selector switch is operated and indicating on the dial the wave band scale for use with the wave band selected by said selector 30 switch.

6. A wave band indicator for a multi-wave band radio set having a wave band selector, comprising a dial having a plurality of concentric scales thereon, each scale corresponding to a 35 selected wave band, a pointer rotatable about a fixed axis to indicate the scale reading, means to move said pointer selectively to any of a plurality of positions in a line passing through its axis of rotation whereby to indicate selectively any wave 40 band scale, and means operably connecting said pointer to said wave band selector to adjust said pointer to a corresponding scale when such wave band selector is moved to select the wave band to which the scale corresponds.

45 7. A wave band indicator for a multi-wave band radio set having a wave band selector, comprising a dial having a plurality of scales thereon, each of said scales corresponding to a wave band, a pointer movable longitudinally to each 50 scale on the dial, said pointer in any position being rotatable about a fixed axis to indicate arcuate relation to the scale, and means continuously operably connecting said pointer to said wave band selector to move said pointer longitudinally 55 to positions in a straight line with said axis to select the wave band to which said scale corresponds.

8. In a multi-wave band radio set, a wave band selector, an indicating dial, a plurality of scales 60 on said dial corresponding to individual wave bands, rotatable indicator means movable in front of said dial, a portion of said indicator means being shiftable with respect to the remainder of the indicator means to positions in 65 a straight-line path through the axis of rotation, and means operably connecting said last named part to the wave band selector whereby the said part will be shifted to various predetermined positions with respect to the wave band 70 selector.

9. A wave band indicator for a multi-band radio set having a wave-band selector comprising a dial having a plurality of scales thereon, each of said scales corresponding to a wave-band, 75

a pointer, said pointer being movable to position with respect to said scale in which position the pointer resides in operative relationship to said scale, said pointer in any position being rotatable about a fixed axis to indicate arcuate relation to the scale, and means operably connecting said

pointer to said wave-band selector to move said pointer to said positions in a straight line with said axis to select the wave-band to which said scale corresponds.
